DRESSMAKER'S PINCUSHION

Hilda E. Einess, 120 Maple St., Crookston, Minn. 56716

Filed Aug. 17, 1967, Ser. No. 8,297

Term of patent 14 years

U.S. Cl. D3—19
Int. Cl. D3—99

FIG. 1 is a perspective view of a dressmaker's pincushion showing my new design;

FIG. 2 is a cross sectional view looking in the direction of the arrows 2—2; and

FIG. 3 is a top plan view thereof.

The essential features of my design are shown in full lines.

I claim:

The ornamental design for a dressmaker's pincushion, as shown and described.
